HEATING AND COOLING SYSTEMS FOR WALLS,
CEILINGS, AND FLOORS

Alfred Wolf, Basel, Switzerland, assignor, by mesne assignments, to Etablissement Alustra, Vaduz, Liechtenstein

Application March 11, 1953, Serial No. 341,731

Claims priority, application Switzerland March 20, 1952

1 Claim. (Cl. 257—124)

The present invention has for its object a heating and cooling system for walls, ceilings and floors, including conductive metallic elements of extended generally flat form and provided with a plaster layer on the side facing the room which is to be heated or cooled. According to the invention in a heating and cooling system of this type, the metal elements are provided on the side carrying the plaster layer with teeth or tongues which are raised out of the plane of the elements after the fashion of splinters cut out of the thickness of the metal element, these tongues producing an increase in the effective area of the metal elements and also forming anchoring means for the plaster layer.

A preferred embodiment of an arrangement according to the invention is illustrated in the accompanying drawings which only show however, as much of the system as is necessary for an understanding of the invention. In the drawings:

Figure 1 shows diagrammatically a portion of the heat-distributing metal sheet forming part of the heat-transferring system;

Figure 2 is a cross-section thereof, with the metal sheet provided with a plaster layer.

The system includes in the usual manner a number of heating or cooling pipes, not shown, spaced with reference to one another and laid inside the ceiling, wall or floor for carrying the flat heat-conduction elements. In the case illustrated, the heat-conducting elements are constituted by metal sheets *a* preferably of aluminum, of which Figure 1 shows a portion. Out of the thickness of said sheet are cut splinter-like tongues *a-1* which, as shown in Figure 1, rise above the surface of the metal sheet to form a comb-like structure. When in position, the metal sheets thus prepared are laid with the tongues

2

facing the room to be heated or cooled. These tongues produce an increase in the surface area of the metal sheets and thus further the exchange of heat through the latter, and they also form anchoring means for the plaster layer usually laid in such arrangements on the metal elements.

Adhesion of the plaster layer to the flat metal elements as provided hitherto, is a difficult problem to solve, and an advantageous solution is provided by the present improved arrangement by the formation of tongues on the metal elements. Generally speaking, the plaster layer includes, as shown in Figure 2, a foundation plaster coat *b* and a finishing plaster coat *c*. The tongues *a-1* are of such length and so bent that when the plaster coats are applied the tips of the tongues *a-1* extend into the finishing plaster coat *c* and so into the immediate vicinity of the outer surface of the plaster. As far as heat distribution is concerned, these tongues show a still further advantage inasmuch as heat or cold is transmitted thereby through the plaster coats which form poor heat-conductive layers up to the immediate vicinity of the outer surface of the finishing plaster coat.

What I claim is:

In combination, a large, flat, heat conducting metal element and at least one layer of plaster on one surface of said element, said element having a plurality of bent, splinter-like teeth of substantially uniform width peeled out of said one surface to a depth less than the thickness of said element, said splinter-like teeth having a thickness less than the thickness of said element and extending into said layer of plaster to a point close to the surface of said layer of plaster, whereby said metal element and plaster may form a part of a wall of a room, said layer of plaster facing the interior of the room, and heat may be supplied to said metal element to be conducted into said plaster layer and radiated into the room through the plaster.
